**COMBINED HOOK, PAD, AND PENCIL HOLDER
ATTACHMENT FOR A WALL TELEPHONE**

Anthony Victor Farina, 227 Michigan St.,
New Kensington, Pa.

Filed Feb. 25, 1960, Ser. No. 59,516

Term of patent 14 years

(Cl. D26—14)

Fig. 1.

Fig. 2.

Fig. 3.

Fig. 1 is a bottom perspective view of a combined hook, pad and pencil holder attachment for a wall telephone showing my new design;

Fig. 2 is a top perspective view thereof; and

Fig. 3 is a side view thereof as viewed from the left of Fig. 1.

The broken line showing of a wall type telephone, pad and pencil in Fig. 3 is for illustrative purposes only.

I claim:

The ornamental design for a combined hook, pad, and pencil holder attachment for a wall telephone, substantially as shown and described.
